SHEET METAL STRUCTURE

Frank C. Watson, Chester, Pa.

Application May 13, 1937, Serial No. 142,450

16 Claims. (Cl. 189—34)

This invention relates to metallic buildings and particularly to sheet metal structures of the general character disclosed in my pending application, Ser. No. 49,388, filed November 12, 1935.

5 The general object of this invention is to provide a light self-contained metallic structure which may be easily and cheaply manufactured and easily erected.

Another object is to provide a metallic structure of this character which may be used either for walls, floors or roofs, so that the entire building may embody the same constructive principle and be formed of practically the same units.

A further object is to provide a structure of this character in which the various units of construction, which are formed of metallic sheets, may be interlocked with each other, these interlocks forming rigidifying elements.

A still further object is to provide a structure in which the inner and outer sheets of the wall or of a ceiling or floor will form, without additional members, a finished surface, and another object is to so form these outer and inner sheets of the wall that the outer sheets may have the appearance of weather boarding or in case of a roof, may have the appearance of tiles or shingles, and in which the inner sheets of the wall permit the application thereto of wall facing slabs held in place between the interlocking joints of the several courses.

Other objects will appear in the course of the following description.

My invention is illustrated in the accompanying drawings wherein:

35 Fig. 1 is an elevation of one end of a wall constructed in accordance with my invention.

Fig. 2 is a top plan view of one of the corrugated strengthening sheets.

40 Fig. 3 is a fragmentary perspective view of the sheet metal members or sections which are used to form the wall shown in Fig. 1, the corrugated sheets, however, being omitted.

Fig. 4 is a fragmentary end elevation of a floor or wall construction in which I-beams are used 45 combined with sheet metal sections as shown in Fig. 3.

Fig. 5 is a like view to Fig. 4 but showing a modified form of I-beam and a modified form of connection between the sheet metal sections.

50 Fig. 6 is an end elevation of the complete I-beam shown in Fig. 5.

Fig. 7 is a fragmentary vertical sectional view through a modified form of inner sheet in which this sheet is formed of metal lath, expanded

metal, wire mesh or perforated metal to which plaster is applied.

In Figs. 1 to 3, I have illustrated a wall structure, though it is to be understood that this structure slightly modified may be used as a floor or 5 a roof. I will first describe the structure, however, as a hollow wall formed of sheet metal elements.

The structure is formed of a plurality of sheet metal units interlocked with each other, the units 10 being articulated at the various courses so as to build up the complete structure. In Figs. 1 and 2, I have shown a plurality of transverse sheets 10 disposed equi-distantly from each other and having any desired length and having a width 15 greater than the width of the completed wall. Extending diagonally with reference to each other and to the sheets or plates 10 are the diagonal sheets 11 and 11^a. The sheet 11 extends downward and inward and is formed with an interlocking fold at its re-entrant corner or middle 20 and then extends upward and outward. The sheet 11^a is of the same form as sheet 11 but is reverse thereto. At the corner of each approximately V-shaped sheet, the sheet is folded to 25 provide a hook 12 of two thicknesses of material and the opposite sheet 11^a is also formed to provide a corresponding hook 13 which is complementary to and interlocks with the hook 12. At 30 their margins the sheets 11 and 11^a extend horizontally outward, as at 14. Disposed between the horizontal margins of the sheets or plates 10 are the inner facing sheets 15 and on the outside of the wall are the sheets 16 which, as shown in Fig. 1, may simulate weather boarding and may, 35 therefore, extend downward and outward on a slant, though this is not absolutely necessary as these outer sheets 16 might extend vertically in the manner of the sheets 15.

Disposed between the portions 14 of the horizontal sheets 10 and inward of the sheets 15 and 16 are the vertically corrugated sheets 17. These may have sharp V-shaped corrugations or sinuous corrugations. The depth of the corrugations is equal to the distance between the sheet 15 and the beginning of the diagonal portions of sheets 11 and 11^a. On the outside of the wall, it will be seen the upper end of the corrugated sheet 17 is equal to the distance between the upper end 40 of the sheet 16 and the beginning of the diagonal portion of sheet 11. At its lower end, however, the sheet 16 is spaced from the corrugated sheet 17. This is due to the fact that the sheet 16 45 simulates weather boarding and is formed par- 50 55

ticularly for the purpose of shedding rain outward of the joint between the courses.

The margins of the sheets 10, 11, 11^a and sheets 15 and 16 are interfolded upon each other 5 at every course. Thus the upper margin of each sheet 15 is extended outward and downward, as at 19, to form a downwardly opening hook. The lower margin of sheet 15 is bent outward at 18, then extended directly downward, 10 then inward and directly upward to form an upwardly opening hook 19^a. The sheet 16 is also formed at its upper end with a downwardly opening hook 19 but at its lower end or margin, the sheet 15 extends directly inward, then upward to 15 form an upwardly opening hook 19^a. The sheets 16 at their margins are downwardly bent at 20 and the sheets 11 and 11^a exteriorly of the horizontal portions 14 are bent straight downward, as at 21. These bends 20 and 21 may be either pre- 20 formed or formed as the several courses are erected.

It will be seen from Fig. 1 that the upwardly extending hook 19^a at the lower end of the sheet 15 embraces the downwardly extending portions 25 20 and 21 at each course, so that thus the sheets are interlocked with each other at these interfolded portions which constitute beads extending longitudinally of the structure. The same thing is true of the connections of the sheets 10, 11 and 30 11^a with the outer sheets 16, except that in order to hold the outer corrugated elements 17 in place, a metallic strip 22 is provided which is folded to 35 form an upwardly extending hook embracing the downwardly extending portions 20 and 21 and having an upper flange 23 which extends inward and upward and bears against the outer face of the corrugated sheet 17, thus holding the lower margin of each corrugated sheet 17 in position 40 between the beginning of the diagonal portion 45 of the sheet 11^a and the edge 23 of this strip 22.

It will be seen that the sheets 15 forming the inner face of the wall may be painted, enameled or otherwise decorated so that these sheets may 45 form an ornamental wall surface without the addition of any other wall surfacing member, but in Fig. 1 I have illustrated the application to the outer face of the sheets 15 of wall surfacing slabs or panels 24. These are disposed between the joints or projecting beads of the courses and, 50 as illustrated, may be held in place by approximately U-shaped slip-on strips forming clips 25 which are flanged at their upper and lower margins to embrace the bead formed by the bends 18 and 19 of the sheets 15 and to extend over 55 the upper and lower margins of the slab 24. These slabs 24 may be made of sound-deadening material or fire-proof material or material designed to give a pleasant-looking, non-metallic surface to the inner face of the wall.

60 It will be noted that the outer sheets 16 each extend downward and outward, then inward and upward so as to entirely embrace the turned-down ends of the sheets 10, 11 and the hook formed at the upper end of each sheet 16, so that the lower 65 margins of the sheets 16 form a water-shed, preventing any possible water from entering the joints between the courses. A finishing slab 24^a may also be used, as shown in Fig. 1, this being disposed between the hook at the upper margin 70 of the sheet 16 and the upwardly extending hook at the lower margin of an upper sheet 16. The lower end of each slab 24^a, however, may be supported by a clip in the form of a strip 26, the inner margin of this strip being bent upward and 75 then downward, while the outer margin is bent

upward over the lower edge of the slab 24^a. The inner margin which is bent to form a downwardly extending hook extends over the upwardly extending hook 19^a at the lower margin of sheet 16. 5

While I have heretofore described this structure as if it were a wall, it will be understood that it is intended to be used for a floor or roof structure and that the various courses may be disposed in a horizontal plane instead of a vertical plane. Of course, where the structure is used as 10 a floor, the spaces between the interlocking folds at the junction of the courses must be filled in with some material which will make the floor even throughout its entire extent. This may be in the form of slabs such as the slabs 24, as shown 15 in Fig. 1, or the intervening spaces between these interfolded joints may be filled in with initially plastic material so as to form a smooth and even floor. This is so obvious that it is not believed necessary to illustrate. Of course, if the structure shown in Fig. 1 is used as a roof, particularly 20 a slanting roof or pitched roof, the sheet 16 will constitute roofing sheets slanted downward and outward as in the case of shingles. Where the structure shown in Fig. 1 is used as a floor, it is 25 obvious that the underface of the structure will constitute the ceiling of a room below.

In some cases and particularly where I-beams or joists are used, the web of the beam or joist will take the place of the transverse plates or 30 sheets 10, thus in Fig. 4, I have shown such a structural element A having an I-form in cross-section. In this case, the sheets 11 and 11^a will have their flat margins 14 abutted against the web of the I-beam with their flanges 21 extending 35 approximately parallel to the inner surface of the flanges of the beam. Each face plate or sheet 15 is formed at one end with an outward angular bend 27, then extended parallel to the plane of the body of the sheet and then is bent inward 40 and rearward to form a hook 28. The opposite end of each face plate 15 is formed with an inward angular bend 29, then extended parallel to the body of the sheet and is then angularly bent outward and backward to form a hook 30. 45

In order to connect these sheets 15 to the adjacent flange of the beam or joist, I provide two sheet metal elongated clips 31 and 35. The clip 31 is folded so as to provide a hook portion 32 at one end. Midway of its length, the strip 50 is bent inward at 33 and is then bent to form a hook 34. The clip 35 is angularly bent at its middle at 36 and is formed at one end with the hook 37.

It will be seen that each clip is adapted to 55 embrace the flange of the I-beam and have its inner margin disposed between the corresponding flange 21 and the corrugated stiffening sheet 17. The hook 34 is disposed outward of the I-beam. The clip 35 at one end is disposed outward of the hook 34. The hook 30 of one sheet 15 is disposed within the hook 34 of clip 31 and the hook portion 32 of the opposite sheet 15 embraces the angular bent ends of the hooks 34 and 30. Thus these elements are interfolded 60 upon each other and connected to the I-beam.

In Figs. 5 and 6, I illustrate another form of I-beam formed of sheet metal. This I-beam B is provided with the two end flanges b and these end flanges are formed with inwardly and outwardly extending portions c. This I-beam is formed as illustrated, of a continuous sheet of metal bent to form the two opposite flanges b and the inwardly extending portion c, the single sheet being connected at the middle of the web 75

of the I-beam by interfolding the two margins of the sheet, as at *d*.

It will be seen that in this construction one end of a sheet *15* is bent inward, then longitudinally and outward and towards the body of the sheet to form the hook *30* previously described. The other end of the sheet *15*, however, is bent to form a hook *28a* which is inserted within the hook *30*, these hook portions *30* and *28a* being in turn disposed within one of the refolded portions *c* of the I-beam *B*. The clips *31* and *35* are not necessary to be used in the construction last described inasmuch as the rebent portion *c* of the I-beam constitutes means 15 for holding the sheets *15* to the I-beam.

In Figs. 4 and 5, I have illustrated means for holding a ceiling or wall insulation and finish, this having the form of slabs or panels *38* held in place by cleats *39* formed of a double thickness of sheet metal, the sheet metal being bent to form the outer portion of the cleat, an inwardly extending shank *40*, and an angular portion *41*, which is disposed within the hook *30* of sheet *15*.

It is to be understood that while I have only shown the interior portion of the wall or floor, yet the opposite wall or portion will be constructed in approximately the same manner as the construction heretofore described. In other words, the upper or top flange of the I-beam is the same as the lower or bottom flange of the beam for floor connections and bearings and the interlocking means described are the same both for the lower or bottom flange of the beam as for the upper or top flange.

It will be seen that in all three forms which I have disclosed, there are horizontal or transverse members either in the form of sheet metal plates *10* or in the form of the I-beams *A* and *B*, that in all these forms there are diagonal bracing sheets *11* and *11a*, that there are outer and inner sheets *15* and *16*, that in all forms there are the vertical or longitudinal corrugated sheets *17* (which in a vertical construction particularly act to support all vertical strains by reason of the strength of the corrugated sheets) and that in all forms, the sheets *10*, *11*, *11a*, *15* and *16* are interfolded at their outer and inner margins.

It will be seen further that the construction which I have devised is hollow, very light and yet strong, that this hollow construction provides for a plurality of dead air spaces, thus to an extent insulating the inner surface of the wall from the outer surface of the wall, and that the preformed sheets may be readily assembled and interconnected with each other. I have provided a perfectly braced continuous load bearing structure inasmuch as the vertical elements are braced and helped by the diagonal elements which also 55 act as beams with the parts below the center or neutral axis in tension and the parts above the neutral axis in compression. All of the metal members or elements of this structure are to be of black sheet metal and painted, dipped or made 60 of the lowest grade of galvanized iron or the highest grade of galvanized iron, steel or other suitable metal.

In Fig. 7, I have illustrated a slight modification of the sheet *15*, in which this sheet is formed 70 of metal lath or perforated sheet metal, wire mesh or other material of like character to which plaster can be applied. The metal lath is designated *15a* in this figure and the plaster is designated *E*. This plaster retaining material *15a* can be used for either of the outer and inner

sheets or for both of these sheets in place of the imperforate sheets *15* and *16* shown in Fig. 1. The corrugated sheet *17* behind the sheet *15a* permits the plaster to pass through the perforations or apertures in the sheet *15a* so that the proper plaster key may be secure at the back of the lath.

When the structure shown in Fig. 1 is used as a floor, the upper sheet, equivalent to the sheet *15*, may be composed of metal lath, perforated sheet metal or the like, and this will act as a reinforcing member for a concrete fill or slab, for either a finished floor or a floor on which more layers of material can be placed to form a finished floor surface.

While I have illustrated a typical structure formed in accordance with my invention obviously I do not wish to be limited to the exact details of this structure or the exact arrangement of the parts except as defined in the appended claims.

What is claimed is:—

1. A metallic structure having a plurality of courses, each course being defined by transverse elements disposed between each two courses, intersecting diagonal sheet metal elements disposed between the transverse elements of the courses and having angular portions at the ends abutting against the lateral margins of the transverse elements and outer parallel sheets for each course disposed at right angles to the transverse sheets, the outer sheet on each course being interlocked with the like sheets of the next adjacent courses and engaged with the transverse and diagonal elements.

2. A metallic structure having a plurality of courses, each course being defined by transverse elements disposed between adjacent courses, approximately V-shaped sheet metal elements interlocked with each other at their re-entrant corners and extending in opposite directions, said sheet metal elements having angular portions at their ends abutting against the lateral margins of the transverse elements and outer parallel facing sheets for each course disposed at approximately right angles to the transverse elements, each of said sheets having an outwardly and downwardly extending hook at one end and an inwardly and upwardly extending hook at the other, the facing sheets on each course being interlocked through said hooks with the like sheets of the next adjacent courses, and means engaging the transverse elements and the ends of the V-shaped elements with said outer casing sheets.

3. A metallic structure having a plurality of courses, each course being defined by transverse elements disposed between adjacent courses, approximately V-shaped sheet metal elements interlocked with each other at their re-entrant corners and extending in opposite directions, said sheet metal elements having angular portions at their ends abutting against the lateral margins of the transverse elements and outer parallel facing sheets for each course disposed at approximately right angles to the transverse elements, each of said sheets having an outwardly and downwardly extending hook at one end and an inwardly and upwardly extending hook at the other, the facing sheets on each course being interlocked through said hooks with the like sheets of the next adjacent courses, means engaging the transverse elements and the ends of the V-shaped elements with said outer casing sheets and panels disposed exteriorly of said facing sheets, and means engaging the interlocked

portions of the facing sheets and holding said panels in place.

4. A metallic structure including approximately parallel transversely spaced outer metallic sheets, 5 transversely extending sheets in spaced relation to each other and extending approximately at right angles to the outer sheets, diagonally disposed sheets extending across the space defined by the outer sheets and the transverse sheets, the 10 adjacent ends of the transverse, the outer and the diagonal sheets being interfolded upon each other and upon the outer faces of the outer sheets.

5. A metallic structure including approximately parallel transversely spaced outer metallic sheets, 15 transversely extending sheets in spaced relation to each other and extending approximately at right angles to the outer sheets, diagonally disposed sheets extending across the space defined by the outer sheets and the transverse sheets, the 20 adjacent ends of the transverse, the outer and the diagonal sheets being interfolded upon each other and upon the outer faces of the outer sheets to thereby form projecting beads extending outward from the outer sheets, panels disposed between said beads, and means engaging the beads and holding the panels in place.

6. A metallic structure having a plurality of courses, each course including outer and inner parallel transversely spaced metallic sheets, 30 transverse elements disposed at the ends of each course and extending approximately at right angles to the metallic sheets, diagonally disposed sheet metal bracing elements intersecting at the center of the space defined by the transverse elements 35 and the first named sheets, the ends of the bracing elements, the transverse elements and the first named sheets being interlocked with each other.

7. A metallic structure having a plurality of 40 courses, each course including outer and inner parallel transversely spaced metallic sheets, transverse elements disposed at the ends of each course and extending approximately at right angles to the metallic sheets, diagonally disposed sheet metal bracing elements intersecting at the 45 center of the space defined by the transverse elements and the first named sheets, the adjacent ends of the diagonal and the transverse sheets being folded in one direction, one end of each 50 outer sheet of one course being folded over in the same direction and the opposite end of the same outer sheet being bent to form a hook embracing all of said folds.

8. A metallic structure having a plurality of 55 courses, each course including outer and inner parallel transversely spaced metallic sheets, transverse elements disposed at the ends of each course and extending approximately at right angles to the outer and inner sheets, diagonally disposed sheet metal bracing elements intersecting at the 60 center of the space defined by the transverse elements and the first named sheets, the diagonal bracing elements and the transverse element being engaged with each other and the 65 outer sheet of one course being interlocked with the outer sheets of the next adjacent courses and with the adjacent portions of the transverse and diagonal elements.

9. A metallic structure including a plurality of 70 spaced parallel transversely extending sheets, diagonal sheets disposed in the space between the transverse sheets and intersecting at the middle of said space, the end margins of the diagonal sheets extending parallel to and bearing against 75 the lateral margins of the transverse sheets, the

end portions of the lateral margins being folded upon each other and outer sheets, each sheet having interlocking engagement with each other at its opposite ends and with the folded margins of the transverse and diagonal sheets. 5

10. A metallic structure including a plurality of spaced parallel transversely extending sheets, diagonal sheets disposed in the space between the transverse sheets and intersecting at the middle of said space, the end margins of the diagonal sheets extending parallel to and bearing against the lateral margins of the transverse sheets, the 10 end portions of the lateral margins being folded upon each other, corrugated sheets disposed between and bearing against the lateral margins of the diagonal sheets, and outer facing sheets, each facing sheet having interlocking engagement at its opposite ends with adjacent facing sheets and with the folded margins of the transverse and diagonal sheets. 15

11. A metallic structure including a plurality of spaced parallel transversely extending sheets, intersecting diagonally extending elements disposed in the space between the transverse sheets, the diagonal elements being formed by two angular opposed sections, the re-entrant corners of which approximate and are interfolded upon each other, the end margins of the diagonal elements extending parallel to and bearing against the lateral margins of transverse sheets, the end portions of the lateral margins being folded upon each other, and outer facing sheets, each sheet having interlocking engagement at its opposite ends with the adjacent ends of like facing sheets and with the folded margins of the transverse 30 and diagonal sheets. 25

12. A metallic structure having a plurality of courses, each course being defined by transverse elements disposed between each two courses, two approximately V-shaped sheet metal elements 40 having their re-entrant corners interlocked with each other, the elements being disposed between the transverse elements, the ends of each V-shaped element having angular portions abutting against the lateral margins of the transverse elements 45 and outer facing sheets for each course disposed approximately at right angles to the transverse sheets and interlocked with the like sheets of the next adjacent courses and engaged with the adjacent ends of the transverse elements 50 and the adjacent ends of the V-shaped elements.

13. A metallic structure formed to provide a plurality of courses, transverse sheet metal elements defining said courses, a pair of approximately V-shaped sheet metal elements disposed 55 between each pair of transverse elements, the adjacent corners of the sheet metal elements being bent to form inner engaging hooks, the outer margins of said V-shaped elements being bent to extend parallel to and bear against the lateral 60 margins of the transverse elements, the lateral margins of the transverse elements and the V-shaped elements being folded upon each other in the same direction, sheet metal facing elements for each course, each facing element being formed 65 with an outwardly and downwardly turned hook at one end and with a relatively deep downwardly and upwardly turned hook-shaped portion at the other end formed and constructed to embrace the folded margins of the transverse and V-shaped 70 elements and have hooked engagement with the first named hook-shaped portion of the facing element of the next adjacent course and corrugated sheet metal elements extending parallel to the facing elements and held in place between 75

said facing elements and the diagonal portions of the V-shaped elements.

14. A metallic structure formed to provide a plurality of courses, transverse sheet metal elements defining said courses, a pair of approximately V-shaped sheet metal elements disposed between each pair of transverse elements, the adjacent corners of the sheet metal elements being bent to form inner engaging hooks, the outer 10 margins of said V-shaped elements being bent to extend parallel to and bear against the lateral margins of the transverse elements, the lateral margins of the transverse elements and the V-shaped elements being folded upon each other 15 in the same direction, sheet metal facing elements for each course, each facing element being formed with an outwardly and downwardly turned hook at one end and with a relatively deep downwardly and upwardly turned hook-shaped portion at the 20 other end formed and constructed to embrace the folded margins of the transverse and V-shaped elements and have hooked engagement with the first named hook-shaped portion of the facing element of the next adjacent course and corrugated sheet metal elements extending parallel to the facing elements and held in place between 25 said facing elements and the diagonal portions of the V-shaped elements, the facing elements on one side of the structure being inclined downward and outward with reference to the facing 30 elements on the opposite side of the structure.

15. A wall structure of the character described, including a plurality of spaced parallel transversely extending sheet metal elements, a pair 35 of approximately V-shaped sheet metal elements disposed between each pair of transverse elements, the V-shaped elements extending in opposite directions and being interlocked at their re-entrant corners at approximately the center

of the space defined by the transverse elements, the outer margins of the V-shaped elements being extended outwardly and bearing flat against the outer margins of the transverse elements, the extremities of the outer margins of the transverse and V-shaped elements being bent downward all in the same direction, inner and outer facing sheets each formed at its upper end with an outwardly and downwardly opening hook-shaped portion and each formed at its lower end with a relatively deep downwardly and upwardly extending hook-shaped portion, this last named hook-shaped portion being constructed and arranged to extend over said folded portions of the transverse and V-shaped elements and to engage 15 with the hook-shaped portion at the upper end of the next adjacent facing sheet, vertically corrugated sheets disposed inward of the facing sheets, the corrugated elements associated with the inner facing sheets being held between these 20 inner facing sheets and the diagonal portions of the V-shaped sheets, the outer facing sheets each extending downward and outward so that the lower end of the facing sheet is in spaced relation to the adjacent corrugated sheet and an element having interfolded engagement with the adjacent folds of the transverse and diagonal sheets and extending inward and bearing against the lower end of the adjacent corrugated sheet to hold it in place against the adjacent diagonal end portion of the corresponding V-shaped element. 25

16. A sheet metal structure formed to provide courses, each course comprising a plurality of sheets folded upon themselves at their outer ends and thus providing a series of beads, panels disposed between said beads, and clips extending over said beads and bearing against the edges of the panels to hold them in place. 35

FRANK C. WATSON.
